ATTORNEYS

UNITED STATES PATENT OFFICE.

GILBERT WESTCOTT GEROW, OF VAIL GATE, NEW YORK.

SHAVING UNIT.

Application filed November 25, 1924. Serial No. 752,171.

To all whom it may concern:

Be it known that I, GILBERT W. GEROW, a citizen of the United States, and a resident of Vail Gate, in the county of Orange and 5 State of New York, have invented a new and Improved Shaving Unit, of which the following is a full, clear, and exact description.

This invention relates to shaving units and has for an object to provide an improved 10 construction wherein the soap and container are so formed as to co-act to present a structure acting as an ordinary shaving mug.

Another object of the invention is to provide a shaving unit wherein the base of the 15 unit is concaved for receiving one end of the soap, the concavity acting to hold the soap in position until all of the same has been used.

In the accompanying drawing—

20 Figure 1 is a view partly in elevation and partly in section, disclosing an embodiment of the invention.

Figure 2 is a side view of a modified base to that shown in Figure 1.

25 Referring to the accompanying drawing by numerals, 1 indicates the base which may be of metal or if preferred, of non-metallic material, said base having reduced extensions 2 and 3 for receiving the end of the 30 cover 4 which may be of any desired material and is intended to snugly fit either of the extensions and be held thereon by friction. The base 1 in addition, is formed with a concaved portion 5 which merges into the 35 hollow portion surrounded by the extension 3. Co-acting with the base 1 is a block 6 of soap which is provided with a convexed bottom end 7 and a concaved top end 8.

40 When it is desired to use the unit in shaving, the cover 4 is removed which, if so desired, might be applied to the surface 2 of the base, thus forming an additional base, standard or handle for the unit. The shaving brush should then be dipped in water and applied to bearded face surface, after 45 which, before again applying the brush to water, said brush should be applied to the concaved end 8 with a rotary motion, thus producing a thick concentrated lather which should be applied to the face and then 50 additional water used to secure the desired free lather on the face surface. By having the concaved end 8 and the block or cake of

55 soap 6 positioned as shown in Figure 1, the structure presents almost an ordinary shaving cup structure as the concavity at end 8 will permit the brush to be freely moved to secure the desired lather in substantially the usual manner. The soap is gradually worn down toward base 1 and in fact, the soap 60 may be used until practically all has been utilized by reason of the concaved recess 5 which holds the soap until the very last.

65 In Figure 1, the extensions 2 and 3 have been shown smooth and the cover 4 has been illustrated as fitting the same snugly while in Figure 2 the base 1' is provided with extensions 2' and 3' threaded exteriorly. When this form of the invention is used, it is designed to have the cover 4 threaded 70 interiorly at the open end for a short distance so as to be screwed into position instead of merely slipped on. Also in Figure 2 it has been provided that extension 3 is interiorly threaded and when this form of the invention is used, it is designed to have the convex end of the block of soap threaded for a 75 short distance in order that it might be screwed into the concaved opening 5 of the base instead of being held in this position by friction as in the structure shown in Figure 1. In manufacturing the device, it is planned to provide an aperture 9 if necessary, to allow the passage of air when cover 4 is placed in position or removed from the 80 annular extension 2 or 3. By reason of annular extension 3, not only will the air be confined in the cover 4 but also when the block 6 is forced into the depression 5 air will be confined in the depression as soon as 85 the block has entered the extension 3 and in order to permit a tight fit of the block 6 and at the same time allow the escape of air when the block or cake of soap is applied to the concaved end of the base by friction, a 90 channel or groove 10, if necessary, is formed in the block of soap which extends upwardly to a point just above the extension 3 as shown in Figure 1.

95 What I claim is:

100 1. A soap holder including a block, oppositely facing reduced circular extensions of equal diameter integral with the block, one of said extensions being hollow, said block having a concavity therein within said 105 hollow extension, adapted to support a cake

of soap, a cylindrical cap member the open end of which is adapted to be optionally fitted over either of said extensions to enclose a cake of soap on the block or to provide a support for the block.

2. A device of the class described in claim 1 wherein the exterior faces of the extensions

are screw-threaded for interlocking engagement with the open end of the cap.

3. A device of the character described in claim 1, wherein the inner face of the hollow extension is ribbed for engagement with the soap.

GILBERT WESTCOTT GEROW.
